CIRCUIT INTERRUPTER

Russell E. Frink, Pittsburgh, and Eugene H. Fischer, Latrobe, Pa., assignors to Westinghouse Electric Corporation, East Pittsburgh, Pa., a corporation of Pennsylvania

Application July 22, 1950, Serial No. 175,332

14 Claims. (Cl. 200—144)

1

This invention relates to circuit interrupters in general, and more particularly to arc extinguishing structures therefor.

A general object of our invention is to provide an improved arc extinguishing structure which will more effectively interrupt the circuit therethrough than has been attained heretofore.

A more specific object is to provide an improved spaced plate type of arc extinguishing structure for circuit interrupters of the air break type, in which improved plate configuration is utilized to more readily assist arc extinction at an early current zero.

A further object is to provide an improved plate material for circuit interrupters of the foregoing type which will have improved electrical characteristics at relatively high temperatures.

A more specific object is to provide an improved refractory type spaced plate arc extinguisher of the type utilizing slotted plates in which longitudinally extending grooves, substantially parallel to the direction of the slots, are utilized to prevent reignition of the extinguished arc after a current zero.

Another object is to provide an improved arc chute in which the arc is made to assume a serpentine or sinuous path as it moves outwardly through the chute in which longitudinally extending grooves are provided to form a lengthened creepage path in parallel with the arc to prevent reignition of the extinguished arc after a current zero.

It is still a further object of our invention to provide an improved refractory material for use in an arc chute against which the arc is moved, the improved electrical characteristics of which will more quickly bring about arc extinction.

A further more specific object is to provide a slotted spaced plate type of arc extinguisher in which the plates are formed of a material having improved electrical characteristics.

Further objects and advantages will readily become apparent upon reading the following specification, taken in conjunction with the drawings, in which

Figure 1 is a side elevational view, partially in vertical section, of a circuit interrupter embodying our invention with the contact structure being shown in the closed circuit position;

Fig. 2 is an enlarged vertical sectional view taken along the line II—II of Fig. 1;

Fig. 3 is a fragmentary plan view in cross-section taken along the line III—III of Fig. 2;

Fig. 4 is a top plan view of a modified type of arc chute embodying our invention;

2

Fig. 5 is a vertical sectional view taken along the line V—V of Fig. 4 showing only the arc chute sub-assembly, and

Fig. 6 is an enlarged plan view in section taken along the line VI—VI of Fig. 5 through one of the fins or projections extending outwardly from one wall of the arc chute of Fig. 4.

Referring to the drawings, and more particularly to Fig. 1 thereof, the reference numeral 1 designates a circuit interrupter of the air break type mounted upon a suitable panel structure 2. Briefly, the circuit interrupter 1 comprises a blow-out coil 3, a U-shaped magnetic circuit 4, contact structure 5 separable to establish an arc and an arc extinguishing structure 6 for quickly effecting the interruption of the established arc.

The contact structure 5 comprises a terminal stud 7 surrounded by a bushing 8 of a suitable insulating material. The terminal stud 7 supports a stationary contact plate 9, the latter in turn supporting a main contact 10, a secondary contact 11 and a relatively stationary arcing contact 12. Another terminal stud, not shown, has pivotally mounted thereon a movable contact arm 13 carrying a movable bridging contact 14, a movable secondary contact 15 and a movable arcing contact 16. Also electrically connected to this second terminal stud, not shown, is a main contact 17.

During the opening operation, pivotal clockwise opening rotative motion of the contact arm 13 takes place caused by the actuation of a suitable mechanism, which forms no part of our invention. The bridging contact 14 first separates from the stationary main contacts 10, 17 to force the series current to pass through the secondary and arcing contacts 11, 15 and 12, 16. Continued opening rotative motion of the contact arm 13 subsequently causes separation between the secondary contacts 11, 15 to force the current to pass through the arcing contacts 12, 16.

Further opening rotative motion of the pivotally mounted movable contact arm 13 causes separation between the arcing contacts 12, 16 to establish an arc therebetween. Because of the loop circuit formed by the two terminal studs, 45 and because of venting provided through the vent 23, the arc, established between the separated arcing contacts 12, 16, will bow upwardly to contact the arc horn 18 in the manner indicated by the broken line 19. The attachment of the left-hand arc terminal to the arcing plate or horn 18 will insert into series circuit the blowout coil 20 which will, upon being energized, magnetize the U-shaped magnetic structure 4 to thereby set up a transverse magnetic field 21 between the pole plates 22, as shown in Fig. 2. This magnetic

field will, of course, be transverse to the arc 19 and will move the latter upwardly into the arc chute 6. The right-hand end of the arc 19 soon transfers to the right-hand arcing horn 24 so that the electrical circuit through the interrupter now comprises terminal stud 7, stationary contact 9, conductor 25, blowout coil 20, left-hand arcing horn 18, the arc 26, right-hand arcing horn 24, flexible conductor 26a, conducting movable contact arm 13 to the other terminal stud for the interrupter, not shown.

As mentioned, the transverse magnetic field 21, set up between the pole plates 22 by the blow-out coil 20, forces the arc 26 upwardly into the arc chute 6 which comprises a plurality of refractory spaced plates 27, which do not evolve gas upon contact with the established arc. It will be observed that each plate 27 has a tapered slot 28 extending inwardly from the lower side 29 thereof with the upper end 30 of the slot 28 slightly off center. That is, the center line 31 of the plate 27 passes slightly to the right of the upper end 30 of the slot 28 of the plate 27 shown in Fig. 2. The immediately adjacent plate 27 of Fig. 2, has its slot 28 turned 180° to that of the slot 28 of the first plate 27 in Fig. 2, so that the second plate 27 has the upper end 30 of its slot 28 disposed to the right of the center line 31 of Fig. 2. The net result is, therefore, that the upper ends 30 of the several slots 28 are staggered about the center line 31, so that when the arc 26 is at the upper ends of the slots 28 it is forced to assume a zig-zag configuration, as more clearly shown in Fig. 3.

For the theory pertaining to the manner of arc interruption in a spaced refractory plate type of arc extinguisher, reference may be had to United States Patent 2,442,199, issued May 25, 1948 to Robert C. Dickinson and Russell E. Frink, and assigned to the assignee of the instant application. This Patent 2,442,199 sets forth in detail the theory of arc extinction which is assumed to take place, and also mentions prior patents which form a background for this type of arc interruption.

It will be observed that each of the plates 27 has provided therein a plurality of small slots or grooves 33 in the surface plane of the plate, on each side thereof, which extend substantially parallel to the direction of the narrow tapered portion 30 of the slot 28, the purpose for which will be more fully described hereinafter. It will also be observed that spacers 34, preferably formed of asbestos rope and cemented to the refractory plates 27, are utilized to space the plates 27 the desired distance apart. The plates 27 and the spacers 34 are cemented together, as mentioned, and together with the arcing horns 18, 24 form a sub-assembly 35, which is placed downwardly within the rectangular arc chute housing 36, the latter being disposed between the pole plates 22 of the blowout structure 4. After the sub-assembly 35 has been placed within the arc chute jacket 36, a pair of insulating holding strips 37 are utilized to prevent the gas pressure from forcing the sub-assembly 35 upwardly out of the arc chute jacket 36. Preferably, bolts 38 are employed to secure the holding strips 37 to the upper edges of the arc chute jacket 36.

The slots 28 may extend in some instances for a distance of 7 to 9 inches from the lower ends 29 of the plates 27. As mentioned, the upper ends 30 of the slots 28 are alternately offset so that when the arc 26 is driven up into these notches or slots 28, it is lengthened, restricted

in cross-section and subjected to the intense de-ionizing action of a powerful, magnetically-induced gas blast. All of these factors directly or indirectly bring about deionization of the arc path, and the arc is compelled to continuously ionize fresh quantities of gas. If at the time interval in the region of current zero, the rate of de-ionization exceeds that at which the arc can produce ionization, and all insulation paths parallel to the arc are able to withstand transient and normal restored voltage, interruption of the arc 26 results.

When an interruption takes place, the gas path which immediately before had been a conductor, does not instantly become a good insulator. At the instant immediately following current zero, the restored voltage transient begins to be impressed across the space previously occupied by the arc, and current starts to flow in the reverse direction. The product of this current and the voltage across the arc chute represents energy which is re-ionizing the gas and further heating the solid insulation. If the rate of de-ionization of the gas path and the rate of conduction of heat away from the surface of the solid insulation is greater than the rate at which the arc is ionizing and heating, then the current will be interrupted. We have found that on many successive interruptions, this leakage current flowed from 0.1 to 0.25 cycle after the point of apparent interruption, and that its current magnitude was greater than 0.1 ampere.

We have also discovered that the limit of interrupting ability of the circuit breaker of the foregoing type is not the ability to build up dielectric strength rapidly in the gas space previously occupied by the arc, but rather, it is the ability to hold voltage over the parallel creepage surfaces formed by the ceramic material from which the insulating plates are made.

Due to the intense heat generated by arcs, even highly refractory insulating materials may become conducting when electrical arcs are applied over their surfaces. Many ceramic refractories which are normally good electrical insulators may decompose or dissociate under arc-ing conditions whereby a portion segregates or volatilizes and the residue becomes electrically conducting. At the instant at which interruption takes place, the surfaces of splitter plates have just been exposed to arc temperatures of, perhaps, several thousand degrees centigrade. When the dielectric strength of the gas adjacent to these plates starts to build up, voltage is impressed across the highly heated surface and current flows on the surface, generating heat. If the surface was so hot initially, or the impressed voltage is so high that this heat is generated more rapidly than it is dissipated, then the surface temperature will rise and it will become even more conducting and may cause a failure in operation of the breaker.

We have found that an unexpected improvement in electrical characteristics can be obtained by making the insulating plates 27 from a ceramic refractory composed of at least 85% by weight of sillimanite, which has exceptionally good electrical characteristics at high temperatures as occur adjacent to electrical arcs.

So-called sillimanite refractories may be composed of one or more of the sillimanite group of aluminosilicate minerals: particularly andalusite, kyanite, and sillimanite. We have obtained particularly good results with plates made of andalusite. The chemical formula for all of

these minerals is $\text{Al}_2\text{O}_3\text{SiO}_2$. Each of them dissociates upon heating at high temperatures to free silica and mullite, $3\text{Al}_2\text{O}_3\text{.2SiO}_2$. However, in this case, the products of decomposition (mullite and silica) are good insulators, even at the high temperatures of electrical arcs.

As an example, the body of a series of refractory plates was prepared from powdered andalusite admixed with a small amount (2% to 4%) of a powdered borosilicate glass, as a fluxing agent, not exceeding 3% by weight of incidental impurities such as alkali oxides and lime, and from 5% to 8% of refractory type ball clay added for bonding. This body should be fired at a sufficiently high temperature, at least pyrometric cone 17, to bring about at least a partial dissociation to develop mullite crystals which greatly improves the strength, thermal resistance, and spalling resistance of the plate. The plates may be fired to provide any desired amount of mullite or even to the extent that they are composed essentially of mullite and a small amount of free silica which melts at approximately 3300° F . This offers the advantage that even though the outermost layers of a plate may be melted by an arc, it will still be a high resistance material which will be beneficial for the reasons set forth.

We will now describe a specific example. In forming 100 pounds of the sillimanite refractory composition 92 parts of powdered andalusite was admixed with three parts of powdered borosilicate glass composed of 80% SiO_2 , 12% B_2O_3 , 7% Al_2O_3 and the balance alkali oxides, as a fluxing agent and five parts of refractory ball clay (essentially aluminum silicate) for bonding with a small amount of water to form a plastic mass. Plates were molded from the composition and fired at 2850° F , plus or minus 50° F .

Sillimanite alone may also be used without any bonding clay or flux such as glass or lime. In the case of the pure material the firing temperature is necessarily higher, above 2900° F . A temporary binder such as dextrin, or polystyrene should be used to bind the particles together to properly mold into plates. During firing the temporary binder is carbonized and burns out.

We have also found that improved performance can be obtained by having the ceramic insulating plates 27 provided with their surfaces grooved, as shown more clearly in Figs. 2 and 3. The grooves 33 in the surface planes of the plates are placed at right angles to the arc, and are sufficiently narrow and deep that the bottoms of the grooves are not directly exposed to the arc. The creepage path in parallel with the arc is then of alternate bands of hot and cold materials, the resistivity of the cold bands being very high. This means that even after a heavy current interruption, the surface over which creepage would take place, as previously described, is so completely broken up by these relatively cold bands that breakdown will not occur due to leakage, and full advantage can be taken of the dielectric recovery of the gaseous arc space. Another advantage will be realized from a structure of plates as described. Such a structure will have a higher interrupting efficiency where interrupting efficiency is defined as

Max. int. voltage
Arc voltage

Arc voltage is largely due to extraction of heat from the arc. It is evident that we have raised

the maximum voltage interrupting ability without altering the structure in such a manner as to increase the heat extracted. Lower arc voltage for a given interrupting voltage is an advantage inasmuch as excessive arc voltage is inclined to produce switching surges.

This feature of the groove construction is applicable to insulating plates regardless of the material from which they are made, sillimanite refractory being preferred, but zircon porcelain, asbestos lumber, or any other refractory material being improved by such grooving.

In a particular instance, the grooves 33 were $\frac{1}{16}$ inch deep and were $\frac{1}{16}$ inch apart between their centers. The width of the bottom of the groove was $\frac{3}{16}$ inch, and the grooves 33 extended approximately $\frac{3}{4}$ inch above the top of the upper end 30 of the slot 28, as shown more clearly in Fig. 2. The grooves 33 extended approximately 1 inch to one side of the slot 28, as shown in Fig. 2, and the distance between the plates 27 was approximately $\frac{1}{8}$ inch, with the plates 27 being substantially $\frac{1}{4}$ inch in thickness. The total width of the plates 27 was substantially $3\frac{1}{2}$ inches. The lateral distance between the upper ends of the offset slots 30 was substantially 1 inch.

Figs. 4-6 illustrate a further embodiment of our invention. This embodiment illustrates the use of our invention in an arc chute 41 of the type consisting of two wall members 42, 43, each of which has projections or fins 44, 45 which interleave with the fins or projections of the opposite wall member. In other words, upon the assembling of the two wall members 42, 43, the arc is made to assume a serpentine or sinuous path as it moves upwardly and outwardly through arc chute 41, as viewed in Fig. 5. It will be noted that the lower ends of the fins 44 and 45 are chamfered or tapered as at 46, 47 so that the arc is made to gradually assume its sinuous path as it moves upwardly along the projections 44, 45 in its upward movement through the arc chute 41.

Preferably a suitable transverse magnetic field set up by blowout structure is utilized in forcing the arc upwardly through the arc chute 41. The wall members 42, 43, together with their integrally formed projections or fins 44, 45 are formed of the sillimanite material hereinbefore referred to. Also preferably, the two sides of each fin or projection 44, 45 have formed thereupon the longitudinally extending grooves 48, as more clearly shown in Fig. 6.

As hereinbefore referred to, when the arc is moved upwardly through the arc chute 41 and is made to assume a sinuous form, the longitudinally extending grooves or irregularities 48 form a lengthened creepage path in parallel with the arc to thereby prevent reignition of the arc after a current zero. As previously explained, the bottoms 48a of the grooves 48 are much cooler than the top plate surface and hence the material has better electrical breakdown characteristics.

Although we have shown and described specific structures and material, it is to be clearly understood that the same were merely for the purpose of illustration, and that changes and modifications may readily be made therein by those skilled in the art, without departing from the spirit and scope of the appended claims.

We claim as our invention:

1. A circuit interrupter of the air-break type including a plurality of closely spaced plates of insulating material having tapered slots provided

therein, the tapered portion of the slot in each plate being offset from the center line of the plate and the plates being alternately assembled with the tapered ends of the slots to the right and to the left of the center line to form a zigzag arc passage, means for establishing an arc, the arc moving within the several slots and into the zigzag arc passage, and a plurality of longitudinally extending grooves on at least one side of each of a plurality of plates adjacent the slot therein to form upon assembling a lengthened creepage path in parallel with the arc after it has assumed a zigzag configuration near the closed ends of the slots.

2. A circuit interrupter of the air-break type including a plurality of closely spaced plates of insulating material having tapered slots provided therein, the tapered portion of the slot in each plate being offset from the center line of the plate and the plates being alternately assembled with the tapered ends of the slots to the right and to the left of the center line to form a zigzag arc passage, means for establishing an arc, the arc moving within the several slots and into the zigzag arc passage, and a plurality of longitudinally extending grooves on both sides of each plate adjacent the slot therein to form upon assembling a lengthened creepage path in parallel with the arc after it has assumed a zigzag configuration near the closed ends of the slots.

3. A circuit interrupter including a plurality of spaced plates, means for establishing an arc and moving the arc against the edges of the plates, and the plates being composed of a sillimanite refractory composed of at least 85% of a mineral composed of $\text{Al}_2\text{O}_3\text{SiO}_2$.

4. A circuit interrupter including means for establishing an arc, an arc chute having insulating portions against which the arc is moved, and the insulating portions being composed of a refractory composed of at least 85% of at least one aluminosilicate mineral selected from the group consisting of $\text{Al}_2\text{O}_3\text{SiO}_2$ and $3\text{Al}_2\text{O}_3\text{.2SiO}_2$.

5. A circuit interrupter of the air-break type including means for establishing an arc, an arc chute having means at least partly of insulating material for causing the arc to assume a sinuous form, and said latter mentioned means having a plurality of grooves extending transversely of the arc to form a lengthened creepage path in parallel with the arc to prevent reignition after a current zero.

6. A circuit interrupter of the air-break type including means for establishing an arc, an arc chute including two side wall members, each having a plurality of outwardly projecting fins, the fins of one wall member closely interleaving with the fins of the opposing wall member, the arc moving into engagement with the fins and thereby being made to assume a sinuous form, and each of a plurality of fins having at least on one side thereof a plurality of longitudinally extending grooves disposed transversely of the arc to form a lengthened creepage path to prevent reignition of the arc after a current zero.

7. A circuit interrupter including means for establishing an arc, an arc chute including a pair of opposing wall members, each of which has a plurality of outwardly extending fins, the fins of one wall member interleaving with the fins of the opposing wall member, the arc moving into engagement with the fins and thereby being made to assume a sinuous form, and the fins being composed of a sillimanite refractory com-

posed of at least 85% of a mineral composed of $\text{Al}_2\text{O}_3\text{SiO}_2$.

5 8. A circuit breaker of the air-break type including means for establishing an arc, an arc chute for extinguishing the arc having plate means at least partly of insulating material for causing the arc to assume a sinuous form, the plate means having a plurality of grooves extending transversely of the arc to form a lengthened creepage path in parallel with the arc to prevent reignition after a current zero.

15 9. A circuit interrupter of the air-break type including means for establishing an arc, an arc chute for extinguishing the arc having plate portions at least partly of insulating material for causing the arc to assume a sinuous form, at least some of the plate portions on at least one side thereof having a plurality of grooves extending transversely of the arc to form a lengthened creepage path in parallel with the arc to prevent reignition after a current zero.

20 10. A circuit interrupter of the air-break type including a plurality of closely spaced plates of insulating material having tapered slots provided therein, the tapered portion of the slot in each plate being offset from the center line of the plate and the plates being alternately assembled with the tapered ends of the slots to the right and to the left of the center line to form a zigzag arc passage, means for establishing an arc, the arc moving within the several slots and into the zigzag arc passage, and a plurality of longitudinally extending grooves in the surface plane of at least one side of at least some of the plates adjacent the slot therein to form upon assembling a lengthened creepage path in parallel with the arc after it has assumed a zigzag configuration near the closed ends of the slots.

25 11. A circuit interrupter of the air-break type including a plurality of closely spaced plates of insulating material having tapered slots provided therein, the tapered portion of the slot in each plate being offset from the center line of the plate and the plates being alternately assembled with the tapered ends of the slots to the right and to the left of the center line to form a zigzag arc passage, means for establishing an arc, the arc moving within the several slots and into the zigzag arc passage, and a plurality of longitudinally extending grooves on both sides of at least some of the plates in the surface planes of such plates adjacent the slot therein to form upon assembling a lengthened creepage path in parallel with the arc after it has assumed a zigzag configuration near the closed ends of the slots.

30 12. A circuit interrupter of the air-break type including means for establishing an arc, an arc chute having plate means at least partly of insulating material for causing the arc to assume a sinuous form, the plate means having a plurality of grooves in the surface planes of the plate means extending transversely of the arc to form a lengthened creepage path in parallel with the arc to prevent reignition after a current zero.

35 13. A circuit interrupter of the air-break type including means for establishing an arc, an arc chute having plate portions at least partly of insulating material for causing the arc to assume a sinuous form, at least some of the plate portions on at least one side thereof having a plurality of grooves in the surface planes of such plate portions extending transversely of the arc to form a lengthened creepage path in parallel

with the arc to prevent reignition after a current zero.

14. A circuit interrupter of the air-break type including means for establishing an arc, an arc chute including two side wall members each having a plurality of outwardly projecting fins, the fins of one wall member closely interleaving with the fins of the opposing wall member, the arc moving into engagement with the fins and thereby being made to assume a sinuous form, and at least some of the fins having at least on one side thereof a plurality of longitudinally extending grooves in the surface planes of the fins disposed transversely of the arc to form a lengthened creepage path to prevent reignition of the arc 15 after a current zero.
